(57) **CLAIM**

The ornamental design for a strap for a shoe, as shown and described.

DESCRIPTION

FIG. 1 is a top perspective view of a strap for a shoe, shown in use, showing my new design;

FIG. 2 is a top plan view thereof;

FIG. 3 is a right side view thereof;

FIG. 4 is a bottom plan view thereof;

FIG. 5 is a left side view thereof;

FIG. 6 is front view thereof; and,

FIG. 7 is a back view thereof.

The light weight broken line portions of FIGS. 3, 7, and 10 are included to show unclaimed subject matter only and form no part of the claimed design.

The heavy broken lines along the periphery of the strap and the buckle strap of FIGS. 1-7 are included to show stitching on the article.
